UNITED STATES PATENT OFFICE.

OTTO BANNER, OF EASTON, PENNSYLVANIA, ASSIGNOR TO INGERSOLL-RAND COMPANY, OF JERSEY CITY, NEW JERSEY, A CORPORATION OF NEW JERSEY.

REGULATING MECHANISM FOR MIXED-PRESSURE ENGINES.

1,105,952.

Specification of Letters Patent.

Patented Aug. 4, 1914.

Application filed January 14, 1914. Serial No. 811,989.

To all whom it may concern:

Be it known that I, OTTO BANNER, a subject of the German Emperor, residing at Easton, in the county of Northampton and State of Pennsylvania, have invented a certain new and useful Improvement in Regulating Mechanism for Mixed-Pressure Engines, of which the following is a specification.

10 This invention relates to regulating mechanism for mixed pressure engines and more particularly to that type of governor wherein in the total amount of steam admitted is controlled by the load on the engine and 15 the proportion of the high and low pressure steam is controlled by the pressure of one of the steam supplies.

The object of this invention is to provide a regulating mechanism of this type 20 which will act positively and powerfully and at the same time will be sensitive to slight variations of load and steam pressure.

With this object in view, I have devised a regulating mechanism, a practical embodiment of which is shown in the accompanying drawings in which:

Figure 1 is a perspective view of the mechanism showing its connection with the engine and Fig. 2 is a vertical longitudinal 30 section through the total steam supply controlling motor and its pilot valve.

The regulator, is shown in connection with a turbine having a casing 1 and a shaft 2 from which a governor 3, conventionally shown, is driven by means of a gear wheel 4 and worm 5. To the movable sleeve of the governor is attached a rod 6 which is pivotally connected to one arm of a bell crank lever 7 which has a stationary fulcrum 8. To the other arm of bell crank lever 7 is pivotally attached a link 9, to the upper end of which is pivoted one end of a controlling lever 10. The other end of the controlling lever 10 is attached to a rod 11 which is secured to a piston 12 sliding in a cylinder 13, this cylinder and piston serving as a total steam supply controlling motor. Hydraulic pressure is admitted to either side of the piston 12 through pipes 14 and 15 by the movement by the valve stem 16 of the pilot valve 17, this arrangement of motor and pilot valve being well known in the art. Pivotally secured near its center on rod 11 is a steam proportion-

ing lever 18, to one end of which is secured, by means of a link 19, an arm 20 the other end of which is secured to a high pressure cam sleeve 21 which rotates on a shaft 22 secured to the valve casing and is provided with a cam 23. To the other end of the lever 18, by means of a link 24, is secured an arm 25 which, by means of levers 26 and 27 and link 28, operates a low pressure cam shaft 29 on which is secured a cam 30. Coacting with these cams 23 and 30 are rollers 31 and 32 which, through the agency of levers 33 and 34, pilot valves 35 and 36 and motors 37 and 38, serve to operate the high and low pressure valve 39 and 40, respectively, of the turbine. The construction and operation of these valve operating motors 37 and 38 and their pilot valves are the same as the total steam supply controlling motor previously described so that further detail is unnecessary. As 75 the engine shown is intended to be operated with live steam only when the exhaust steam is not sufficient, there is attached to the arm 20, a rod 41 provided with a piston 42 on its lower end which slides in a cylinder 43. 80 A spring 44 tends to keep the piston 42 at the bottom of the cylinder and hence keep the arm 20 depressed and the cam 23 in a position so that valve 39 will be closed. It will be evident therefore that under ordinary conditions movement of the governor 3 and hence of the lever 18 will be communicated only to the low pressure valve, spring 44 holding the arm 20 and hence the connecting end of the lever stationary. This 90 will occur only when the low pressure steam is sufficient to operate the engine. When the low pressure steam is insufficient another mechanism comes into operation. To the upper side of a piston 45 which slides in a cylinder 46 a pipe 47 leads to the low pressure steam main. A spring 48 tends to move the piston 45 upwardly when the pressure of the low pressure steam falls off. The piston 45 is attached to a rod 49 which by means of a lever 50, pilot valve 51 and motor 52, such as already described, communicates an opposite motion to a rod 53. To the rod 53 is attached an arm 54 secured to a sleeve 55 which is journaled 100 on the shaft 22 concentrically with a sleeve 56 secured to the arm 25. The sleeve 55 has a longitudinally projecting lug 57 which

is adapted to engage a similar lug 58 on the sleeve 56 when the arm 54 has been moved a certain distance downwardly.

In operation, when the speed of the engine decreases the rod 6 will be moved outwardly lowering the nearer end of lever 10 and hence raising the rod 11 and with it the lever 18. If the low pressure steam is sufficient the only effect this movement will have 5 will be to raise the arm 25 through the link 24 and rotate the cam shaft 29 to the left lowering the lever 34 and opening the low pressure valve 40 to a greater extent. If, however, the low pressure steam is not sufficient 10 the position of piston 45 and hence lug 57 will be such that the arm 25 can have no further upward movement. In such a case the movement of the lever 18 will be communicated to the arm 20 and overcoming 15 the spring 44 will rotate cam 23 to the left opening the high pressure steam valve. Furthermore, if the load on the engine should remain constant and the amount of 20 low pressure steam and hence its pressure decrease a movement of the rod 49 upwardly would take place accompanied by a corresponding downward movement of the arm 54. As soon as the lug 57 comes into contact with the lug 58, the arm 25 would be 25 moved downwardly shutting off the low pressure valve to a corresponding extent and as the rod 11 would remain stationary this downward movement of the arm 25 would produce an upward movement of the 30 arm 20 opening the high pressure valve.

It is to be understood that the present showing and description discloses only one specified modification of my invention and other forms and modifications are included 40 in the spirit and scope of the invention as expressed in the claims.

What I claim is:

1. In a regulator for mixed pressure engines, a high pressure steam valve, a low 45 pressure steam valve, motors for moving said valves, cams for governing the action of said motors, cam shafts for said cams, an element movable in accordance with the load of the engine, a lever pivoted on said 50 element, a connection between one end of said lever and said high pressure cam shaft,

a connection between the other end of said lever and said low pressure cam shaft, a second element movable in accordance with the pressure of the low pressure steam, a 55 connection between said second movable element and said low pressure cam shaft arranged to engage said cam shaft and turn it to close said low pressure valve when the low pressure steam falls off, and resilient 60 means tending to hold said high pressure cam shaft in a position to close its valve.

2. In a regulator for mixed pressure engines, a high pressure steam valve, a low pressure steam valve, a cam shaft for operating said low pressure valve, an element movable in accordance with the low pressure steam pressure, an arm connected to said movable element, a sleeve on said arm journaled adjacent to said cam shaft, a lug 70 on said sleeve for engaging and turning said cam shaft to close the low pressure valve when the low pressure steam falls off, and means to cause the closing of said low pressure valve to open said high pressure 75 valve.

3. In a regulator for mixed pressure engines, a high pressure steam valve, a low pressure steam valve, cam shafts for operating said valves, an element movable 80 according to the load of the engine, a lever pivoted on said element, an arm for moving said high pressure cam shaft attached to one end of said lever, an arm for moving said low pressure cam shaft attached to the 85 other end of said lever, resilient means tending to keep said high pressure cam shaft in a position to close its valve, a second movable element moving in accordance with the pressure of the low pressure steam, and an 90 arm attached to said second movable element having a connection with said low pressure cam shaft adapted to move it to close its valve when the low pressure steam falls off, said motion being transmitted to 95 said lever to open said high pressure valve.

In testimony whereof, I have hereunto set my hand.

OTTO BANNER.
